KNITTING MACHINE

Franz Meiwald, Vienna, Austria

Application May 21, 1932, Serial No. 612,688
In Austria August 7, 1931

5 Claims. (Cl. 66—9)

My invention relates to improvements in devices for producing tubular coverings such as are used for instance for electric conductors or other strand elements.

5 It has already been proposed to surround conductors, particularly electric cables, instead of with the usual braided covering, with a knitted covering so as to protect the insulation as well as for insulating purposes, since a considerable saving in material and in operating time is thus attained in view of the greater efficiency of the knitting machine as compared to the high-speed braiding machine. Such a device and products manufactured with it are disclosed for instance 10 in my U. S. Patents Nos. 1,814,324 and 1,936,519, on which the present invention is an improvement. As the saving increases with increasing length of the loop, the tendency has been therefore to increase the loop length as far as possible. 15 This, however, impairs the appearance of the tubular covering, since the rows of wales spaced apart a distance equal to the length of the loops project from the tubular covering, thus rendering the surface irregular. This is particularly 20 the case, if columns of knitted loops are for special reasons arranged spirally such as the disclosures in my aforementioned patents show, as the loops then form, between adjacent wale rows, the cords for a cylindrical surface formed by the 25 spiral rows of wales, and these loops therefore lie lower than the wale rows, so that the latter become undesirably prominent.

In circum-knitting cores such as electric conductors or similar strand elements with any form 30 of knitting, it is of great importance that the speed at which the core is supplied to the knitting head be always in suitable relation to the speed at which the circum-knitted fabric is produced by the knitting head, since otherwise 35 either the fabric becomes too loose and fails in its protective purpose, or it becomes too tight and thus causes breakage of its constituent threads. While it has been proposed in the prior art to 40 positively gear the supply device for the core to the rotary elements of the knitting head, to secure a certain desired ratio of the operating speeds of these elements, such positive gearing is 45 insufficient since the knitting process involves in addition a number of variable functions which readily may upset the desired effect of such fixed geared speed ratios and produce the defects 50 aforementioned.

It is the purpose of my invention to provide means for additional correction and exact adjustment of the speed ratio between the core

feed and the production of the knitted fabric which may be readily varied at will to suit the prevailing knitting conditions and by which any desired close or loose fitting of the knitted covering to the core can be attained.

5 While I have illustrated and described my invention with reference to the preferred form of circum-knitting a core with a covering in which the bights of the loops of adjacent courses form a zigzag line following the direction of the loop 10 courses, the particular speed ratio control arrangement between the core speed and the knitting speed shown may be applied without change in principle to the ordinary single thread knitting of a covering around a core in which case 15 it is likewise important to maintain the proper speed ratio.

The invention is represented in Figures 1-7. Figure 1 discloses one of the designs which represents according to the invention one of the 20 different possible bonds of loops, knitted around a core. Figure 2 shows diagrammatically the knitting devices with the needle cylinder and the corresponding cam rings for producing covering for a core according to Figure 1. Figure 3 represents diagrammatically the knitting machine, with the knitting head cooperating with the device over which the object passes which is to be surrounded with a tubular covering. Figure 4 represents an end elevation of the sheave 13 of 25 Figure 3. Figure 5 represents a view partly in longitudinal section and in larger scale, of the type of knitting head shown in Figs. 2 and 3 provided with two cam rings. Figure 6 is a top 30 view of one half of the knitting head, Figure 5, 35 the other half representing a transverse sectional view taken on the line 6—6 of Figure 5, and Figure 7 represents the development of a cam ring particularly adapted to produce the 40 tubular covering involved in Figures 1 and 2.

In the design shown in Figure 1, adjacent loops of each row, while of equal lengths, have long floats between them, and between these loops extend partway the loops of the next succeeding row, overlying with their long floats 8 the loops of the 45 preceding row so as to attain the effect described and claimed specifically in my U. S. Patent No. 1,947,302. For instance as shown in Figure 1, the loops of succeeding rows are staggered an amount equal to half the length of the loops so 50 that the alternately succeeding loop heads 9, 10 of the two rows form a much deeper zigzag line 11 around core 7. The cam ring 4 (Figure 2) has accordingly two grooves 5 and 6 each with two high points. Circumferentially successive

high points are displaced by 90°. Successive needles in the bed are guided alternately in the upper and lower groove. The knitting operation is carried out at the same time with four threads, which pass over thread guides displaced 90° (not shown in Figure 2). In the diagram Figure 2 only two needles are visible and the threads are not shown. This matter is, however, clearly illustrated in Figures 1, 4, and 5 of my U. S. Patent No. 2,006,275, the application for which was filed of even date with the present application.

Other methods of knitting may also be employed in order to attain an arrangement of staggered loops. With the above-mentioned arrangements, it is possible to knit several rows of loops at the same time, so that the circumferentially successive binding points of successive rows of loops are staggered. All or a portion of the binding points of the various rows of loops may, however, be also staggered with respect to the other rows of loops. It is also possible to obtain other kinds of interlacings by the use of two or more cam rings having cam grooves with one or more rises, the cam rings being disposed in axial alignment one above the other, and offset in circumferential direction as shown in my aforementioned Patent No. 2,006,275 so that in axial direction the peaks of one groove register with the valleys of the groove of the adjacent ring, similar to the manner shown in Figure 2 of the present application, except that the two grooves there shown are disposed on the same ring. The cam paths should have in that case at their low points a straight portion similar to the manner shown in Figure 2. In this manner a formation of superposed loops is obtained.

In order that undue yarn tensions may not occur during the knitting which might cause a breakage of the yarns, the central core 12 is fed into the knitting head at a speed which differs slightly from the speed with which the tubular covering leaves the knitting machine. In this way yarn tensions cannot occur as a result of the thread adhering to the central core passing through the knitting device at a high speed. In the case of a single-thread covering with loops positioned parallel with the core axis, the core advances the length of a loop at each revolution of the needle cylinder or cam ring. In the case of a multiple-thread covering with the loops positioned in parallel with the core, the core advances for each rotation of the needle cylinder as many times the length of a loop unit as there are threads distributed on the periphery of the core.

In the case of a knitted tubular covering with loops which are positioned at an angle to the core axis, as is shown in my aforementioned patents, the feeding speed of the core varies in accordance with the cosine of this angle. In order to maintain the prescribed speed of the core, the core passes over a feed control device which is positively timed with relation to the knitting head speed and cam speed to suit the kind of knitting on hand. This device is preferably disposed ahead of the knitting head in the direction in which the core moves, so that it controls the core feed into the knitting head. It may, however, be also arranged in similar manner behind the knitting head or the movement of the core may in similar manner be effected at both points.

In Figure 3, which shows the core speed control device ahead of the knitting head, 12 denotes the central core to be provided with a tubular covering. The core to be covered passes over a sheave 13 and through the knitting-device 14

which is driven by the shaft 16 through the bevel gear 15. The feeding sheave 13 is driven positively by means of the gears 17—24. The core 12, as will be seen from Figure 4, is wound several times around sheave 13 to secure a better grip.

The knitting head is shown partly in section in Figure 5. 25 denotes the needle cylinder, 26 the knitting needles, 27 the upper and 28 the lower cam ring. The position of both cam rings is 10 adjustable with the aid of the shoulder screws 29, 31 taking into the upper cam ring 27, and 30, 31 taking into the lower cam ring 28 through vertical slots on opposite sides of the casing 34. This provides for the rough vertical adjustment 15 of the cam rings. Circumferential adjustment of the rings is possible by the same means, for instance for cam 27, by removing shoulder screws 29 and 31 sufficiently to disengage the cam ring, whereupon the latter may be turned 20 180°, and the screws 29 and 31 be reinserted and tightened. With the number of diametrically opposed screw holes in the cam rings spaced suitable peripheral distances apart, the cam rings may thus be conveniently peripherally adjusted. 25

The needle cylinder is rotatably mounted in cam rings 27 and 28 and vertically supported on its hollow driving shaft 32 with which it is removably coupled by means of a square end, 32'. In order to hold the needle cylinder firmly in 30 coupled engagement, and to avoid vertical vibrations of the cylinder at its high operating speeds, a coil spring 25a is provided on the lower, slender portion of the cylinder, which spring is in engagement at its lower end with the lower cylinder 35 portion, and abuts at its upper end through a ball bearing 46 against a shoulder 45 provided in the interior of the cam ring housing 34'. Thus the needle cylinder is always firmly pressed against the end of its driving shaft 32. This 40 latter shaft is journaled in a stud 49 which forms part of the machine frame (not shown) and which thus rotatably supports the entire knitting head.

The casing 34' which contains the cam rings 45 has a suitable drive connection with the sleeve 33a of a cam ring driving gear 33, the latter being also rotatably supported on the previously mentioned machine frame stud 49 by means of ball bearing 48, so that it can rotate independently 50 of the needle cylinder. As Fig. 3 shows, cam ring gear 33 is driven by the same bevel gear 15 which operates shaft 32 of the needle cylinder, but at the desired speed ratio with respect to the shaft 32, produced by gear train 50 in Fig. 3. 55

The lower end of cam casing 34', ahead of the point of its driving engagement with drive sleeve 33a, is provided with a fine thread with which it is threaded into an adjusting sleeve 34 which slides over the end of sleeve 33a. This sleeve 34 60 serves to effect a fine vertical adjustment of the cam rings and thus of the effective needle throw with respect to the upper rim 25c of the needle cylinder over which the knitted loops bend before they slide into the interior of the cylinder in the 65 usual way. The coarse vertical adjustment of the cam rings by means of screws 29—31 has already been mentioned above and serves a similar purpose. By these coarse and fine adjustments the length of the loops formed by the 70 needles can be very accurately adjusted within the total range of needle throw. Inasmuch as the amount of tubular knitting delivered by the head depends not only upon the rotary speed of the head, but also upon the length of the

loops, this coarse and fine regulation of the loop length forms a very important and critical factor in adapting the knitting speed correctly to the prevailing speed at which the core is fed into the knitting head. Such convenient adjustment between the two speeds is, of course, not possible merely with the gearing between the core speed and the cylinder speed as shown at 15-23 and at 50 in Fig. 3 which is more or less fixed for the time being and constitutes in reality only an approximate relation between the two speeds. In order that the needle cylinder may be easily removed it is held down, as shown in Figs. 5 and 6, by means of a bayonet joint ring 35 within which adjustment sleeve 34 can be turned for adjustment in the manner shown in Fig. 5. This ring 35 is provided with two diametrically oppositely disposed circular slots 36, of which one is clearly shown in Fig. 6, and in each of which one of the thumb screws 37 is located. These screws are threaded into a ring 38 which is socketed on and suitably attached to sleeve 33^a of gear 33. By loosening thumb screw 37, and by turning ring 35 a short distance in clockwise direction (Figure 6) until slots 36 are out of range of screws 37 and are brought into registry with clearance notch 39 in the ring, the latter can be lifted off its seat in portion 38 and the knitting head, including the needle cylinder and cam ring housing 34' can be pulled out of sleeve 33^a. Spring 25^a previously mentioned assists in this lifting operation. When screws 37 tighten the bayonet ring 35 down, fine adjusting sleeve 34 is at the same time locked in its adjusted position against ring 38.

This knitting head and the core feeding mechanism as described and shown may serve for any suitable form of knitting, for instance such as is shown in Figures 1 and 2, the two separate cam rings 27 and 28 representing in particular the cam arrangement of Figure 2, except for the separation of the rings in Figure 5, which as appears from the foregoing description merely facilitates the relative positioning of the cams. As soon as the cams in Figure 5 are adjusted and fixed in their desired relative positions, the cam system operates as shown in and described with respect to Figure 2, and produces the knitting shown in Figure 1.

A further suitable design of the machine consists in designing the cam ring for the operation of the knitting needles with different angles of the needle advancing and retracting groove portions with respect to the central axis of the system. The cam groove is so designed that the angle of inclination of the needle retracting groove branch to the axis of rotation of the knitting device is smaller than the inclination of the angle of the needle advancing groove branch to the same axis. This design of the cam groove has the advantage that more cam elements may be accommodated within a given peripheral length of the cam cylinder than has hitherto been possible, so that the number of operations for a needle is increased accordingly, which renders the system most efficient. If one is, however, not bound to the diameter of the cam ring cylinder, its diameter, while maintaining the output, may be decreased in accordance with the steepness of the angle of the needle retracting groove branch. In this way, a decrease of the weight of the knitting head is brought about which effects on the one hand a saving in material, so that lighter supporting members may be provided, and on the other hand advantages are

attained in operation, owing to the reduced weight of the gyrating masses. The invention is applicable to knitting machines of every description, for instance to machines with two or more systems of cam grooves. The invention is equally applicable to other textile machines with cam groove controls.

A cam groove with differently inclined branches is shown diagrammatically by way of example in Figure 7 which shows the development of a cam groove in the plane of the drawings. The cam groove 42 has four needle advancing paths and four idling paths. The cam ring moves in the direction of the arrow 43. The angle of the needle advancing groove branch to the horizontal line amounts to 42° and the angle of the needle retracting groove branch amounts to 52°. The needles will, consequently, advance slowly and retract rapidly.

Central cores, such as electric conductors, cables 20 with or without lead sheaths, flexible cores for telephones, rubber tube insulated conductors, cab-tire metal sheathed wires may be provided with a tubular covering on the above-described knitting machine.

The knitted tubular covering applied to the insulation of the conductor may be according to the invention improved by calendering and treating it with conventional dressing agents such as gelatine, solutions of starch, sugar or the like, by machines not shown here, as soon as it leaves the knitting machine. The knitted tubular covering is thus an excellent substitute for a braided tubular covering with dressing, since in the present case the dressing agent penetrates the complete layer of the tubular covering and strengthens not only the individual threads, but also causes the binding points to adhere closely, which increases considerably the strength and the stability of form of the tubular covering.

I claim as my invention:

1. In a machine for knitting a covering around a core, a knitting head including a needle cylinder having needles and at least one cam ring for operating said needles, means positively 45 geared to said knitting head for moving said core through the knitting head in fixed speed relation to the operating speed of the head, and means for adjusting in axial direction the distance between said cam ring and the top rim of said 50 needle cylinder for adjusting the effective length of the looping stroke of said needles to correlate the speed at which the knitted covering is produced to the core speed.

2. In a machine for knitting a covering around 55 a core, a knitting head including a needle cylinder having needles and axially spaced cam rings surrounding said cylinder for operating said needles, means positively geared to said knitting head for moving said core through the knitting 60 head in fixed speed relation to the operating speed of the head, and means for adjusting in axial direction the distance between said cam rings and the top rim of said needle cylinder, for adjusting the effective length of the looping 65 stroke of said needles to correlate the speed at which the knitted covering is produced to the core speed.

3. In a machine for knitting a covering around 70 a core, a knitting head including a base, a needle cylinder disposed within said base and having needles and axially spaced cam rings surrounding said cylinder for operating said needles, means positively geared to said knitting head for moving said core through the needle cylinder in fixed 75

- speed relation to the operating speed of the knitting head, and means for adjusting said cam rings in axial direction with relation to one another and to the top rim of said needle cylinder, said means comprising a cam ring carrier supported within said base and set screws in said rings adapted to be tightened against said carrier for coarsely adjusting said rings in axial direction, and a sleeve finely threaded onto said carrier for supporting said carrier on said base and for axially displacing said carrier with relation to the top rim of said needle cylinder, to coarsely and finely adjust the effective length of the looping stroke of said needles, for correlating the speed at which the knitted covering is produced to the speed of the core.
4. In a machine for knitting a covering around a core, a knitting head including a base, a needle cylinder disposed within said base and having needles and axially spaced cam rings surrounding said cylinder for operating said needles, means positively geared to said knitting head for feeding said core through the needle cylinder in fixed speed relation to the operating speed of the knitting head, and means for adjusting said cam rings in axial direction with relation to one another and to the top rim of said needle cylinder, said means comprising a cam ring carrier supported within said base and set screws in said rings adapted to be tightened against said carrier for coarsely adjusting said rings in axial direction.

tion, and a sleeve finely threaded onto said carrier for supporting said carrier on said base, and for axially displacing said carrier with relation to the top rim of said needle cylinder, to coarsely and finely adjust the effective length of the looping stroke of said needles, for correlating the speed at which the knitted covering is produced to the core speed, and a bayonet joint for attaching said threaded sleeve to said base.

5. In a machine for knitting a covering around a core, a knitting head consisting of a needle cylinder having needles and cam rings surrounding said cylinder for operating said needles, a housing for said cam rings, a supporting stud for rotatably supporting said needle cylinder and said housing and a spring between said cylinder and said housing for maintaining the desired relation between said two elements in axial direction, means positively geared to said needle cylinder and to said cam ring housing for moving said core through the knitting head to correlate the core feed to the operating speed of the head, and means for coarsely and finely adjusting said cam rings in axial direction with respect to the top rim of said needle cylinder for setting the effective length of the looping stroke of the needles, to permit adjustment of the knitting speed of the knitting head with relation to the core speed, and means for locking said axial cam ring adjustments.

FRANZ MEIWALD.
